UNITED STATES PATENT OFFICE.

VIRGIL T. GRAES, OF KING, NORTH CAROLINA.

PRESS.

Application filed December 7, 1925. Serial No. 73,731.

This invention relates to a press, especially adapted for use in connection with hogsheads and similar containers for pressing tobacco and other material of a similar nature. Inasmuch as these hogsheads are quite large and heavy when filled, it is preferred to use a portable press, which may be moved from one hogshead to another, instead of moving each hogshead up to a stationary press.

The objects of the invention include the provision of simple, practical and convenient means for engaging the bottom of the container without raising the latter from the ground, and for forcing the packer down into the upper end of the container with great pressure, and particularly means which may be securely clamped around and under the container, and which will relieve the bottom hoop of all strain while pressure is being applied, at the same time positively holding the bottom so that it can not be pushed out.

The means by which the above objects are attained, and the manner in which the same is operated will be more specifically described in connection with the accompanying drawings illustrating a preferred embodiment of the invention.

30 In the drawings:

Figure 1 is a side elevation of the invention in operative position.

Figure 2 is a plan view thereof.

Figure 3 is a fragmentary section showing the means for operating the clamp which engages the bottom of the container.

Figure 4 is a vertical transverse section showing the means for operating the packer.

Figure 5 is a horizontal section taken on the line 5—5 of Figure 4.

Figure 6 is a vertical section taken on the line 6—6 of Figure 4.

Figure 7 is a vertical section through the bottom of the container showing the clamp applied thereto.

The invention is shown in connection with a hogshead, represented at 10, and having top and bottom hoops 11. The hogshead is provided with a bottom head 12, and with a top head 13, which is secured after the tobacco 14 has been pressed in the hogshead to fill the same. After the tobacco has been laid in the hogshead, the head 13 is forced downwardly to press the same by a suitable pressing device which, in the present embodiment, comprises packers 15, which are

adapted to be forced downwardly by means of ratchet bars 16.

In its preferred form, each of the ratchet bars 16 is formed with series of oppositely disposed teeth 17 in staggered relation, and the mechanism for actuating the same is mounted in a frame 18, having at each end a cross head 19 having attaching members 20 secured thereto and overhanging the edges of the hogshead. These attaching members have upturned or hook-shaped ends 21, which are slotted to engage chains 22, which are connected to a clamping device adapted to be attached to the bottom of the hogshead.

Guide brackets 23 are secured to the ends of the frame 18, and the ratchet bars 16 are guided for vertical movement therein. Each ratchet bar 16 is adapted to be forced downwardly by mechanism which includes a pair of toggles, each consisting of a pair of links 24 and 25. The link 24 is mounted at its upper end on a pin 26 secured in the bracket 23, and the adjacent ends of the links 24 and 25 are connected by a pin 27 secured in a frame 28, which straddles the bar 16 and has an oscillatory movement with respect thereto. The lower end of each toggle link 25 terminates in a tooth 29, adapted to engage successive teeth 17 on the ratchet bar 16 as the latter is forced downwardly, the link 25 being urged toward the ratchet bar by an expansile coiled spring 30 mounted at its ends on bosses 31 and 32 formed on the link 25 and the frame 18, respectively.

The sides of the frame 28 are extended at one end, and have a pivot pin 33 mounted therein to the ends of which a yoke 34 is connected. The ends of the yoke are journaled on a crank 35 formed in a shaft 36, which is journaled in the frame 18, and adapted to be rotated by a hand wheel 37, or equivalent device secured to one end thereof. It will be understood, therefore, that as the shaft 36 is rotated, the frame 28 is oscillated to and fro, and the pairs of toggle links 24, 25 are alternately straightened, and when one pair of links is straightened to force the ratchet bar and packer downwardly, the other pair is contracted, so as to engage the succeeding tooth on the bar. Thus, the packer is moved downwardly step by step while the shaft 36 is rotated.

A rock shaft 38 is mounted in cross bars 39 of the frame 18, and is positioned adjacent

each ratchet bar 17 with a cross head 40, to the ends of which links 41 are connected. Each of these links has a slotted connection with a pin 42 secured in the corresponding toggle link 25. These slots are of sufficient length to permit the normal operation of the toggle links upon rotation of the shaft 36, while the shaft 38 and cross head 40 are in the position shown in Figures 2 and 4. The rock shaft 38, however, has an arm 43 secured thereto by means of which it may be rocked until the cross heads 40 are substantially in horizontal position. This throws the lower ends of the toggle links 25 outwardly against the pressure of the springs 30 and positively releases the ratchet bars 16, and permits a free upward movement of the packers 15.

When operating the press, in order to hold the frame down, the chains 22 are attached to the members 20. The lower end of each of these chains is connected to a pair of braces 44, and these braces carry semi-circular clamping members 45 at their lower ends. These clamping members are of such shape and size as to fit around the lower hoop 11, and to substantially surround the lower end of the hogshead. The lower edges of the clamping members 45 have inverted flanges 46 which have sharpened edges, whereby they may be forced underneath the edges of the hogshead when the clamping members are drawn together.

For manipulating the clamping members 45, one of them has a plate or strap 47 secured to each end thereof in which is mounted a pin or bolt 48, forming the fulcrum of a lever 49. Each of these levers has an eye or U-bolt 50 secured a short distance from the fulcrum and supporting a chain 51, one of the links of which may be engaged with a hook 52 secured to the adjacent end of the other clamping member. It will be seen, therefore, that when the clamping members 45 are placed in opposed relation adjacent the bottom of the hogshead, the levers 49 and chains 51 may be manipulated so as to force the flanges 46 underneath the edges of the hogshead without lifting the latter from the floor.

From the foregoing description, it will be seen that a press constructed according to the invention may be made comparatively light, and yet capable of exerting great pressure. The entire device may be easily carried from one part of the warehouse to another by one man, and may be used in pressing one hogshead after another, without altering the position of the hogsheads. This greatly facilitates the work, since the hogsheads are quite heavy, and it has heretofore required several men to handle them where a stationary press has been used.

Not only is it a very simple matter for one man to adjust the clamping members

45, and to force the same into operative relation to the bottom of the hogshead, but, when so applied, the pressure of the clamping members relieves the strain on the lower hoop 11, and positively prevents the bottom 12 from being forced out when pressure is applied to the head of the hogshead.

While the invention has been illustrated and described in connection with a ratchet device for forcing the head downwardly, it is to be understood that any other equivalent device may be used for this purpose. It is also to be understood that the structure of the clamp and the means for attaching the same to the packer operating mechanism is not limited to the precise form herein shown and described, but that various modifications may be made therein within the scope of what is claimed without any material departure from the salient features of the invention, and without sacrificing any of the advantages of the same.

What is claimed is:

1. A device for pressing material in a hogshead or similar container, comprising a portable frame with attaching members which project over the edges of the container when the frame is placed in operative position, a pair of complementary clamping members, means for suspending the latter from the attaching members, means for drawing the clamping members into engagement with the bottom hoop and the bottom edges of the container, and means mounted in said frame and cooperating with the clamping members to press material which has been placed in the container.

2. A device for pressing material in a hogshead or similar container, comprising a pair of opposed complementary clamping members shaped to conform to the bottom edge of the container and each having an internal flange with a sharpened edge, means for drawing said clamping members inwardly so as to force said sharpened edges underneath the edges of the container as the latter rests on the floor, and means adapted to be connected to said clamping members and operable to press material which has been placed in the container.

3. A device for pressing material in a hogshead or similar container, comprising a pair of opposed complementary clamping members having means to engage the outer surface of the bottom hoop and adapted to extend underneath the bottom of the container, means to draw the clamping members inwardly to relieve the strain on said hoop and to prevent the bottom from being pushed out, and means cooperating with the clamping members to press material which has been placed in the container.

4. A device for pressing material in a hogshead or similar container, comprising a

pair of opposed complementary clamping members shaped to fit around the bottom hoop of the container and underneath the bottom edge thereof, upwardly extending 5 braces attached to the clamping members and arranged in pairs with the members of each pair meeting at their upper ends and having a flexible suspension member connected thereto, a portable frame provided 10 with means for attaching said suspension members thereto, and means cooperating with said portable frame and the clamping members to press material in the container.

5. A device for pressing material in a 15 hogshead or similar container, comprising a pair of opposed clamping members having means to engage the outer surface of the bottom hoop and adapted to extend underneath the bottom of the container, upwardly 20 extending braces attached to the clamping members and arranged in pairs with the members of each pair meeting at their upper ends and having a flexible suspension member connected thereto, a portable frame 25 adapted to be placed over the container and provided with means for attaching said suspension members thereto, means to draw the clamping members inwardly to relieve the strain on said hoop and to prevent the bottom 30 of the container from being pushed out, and means cooperating with said portable frame and the clamping members to press material in the container.

6. A device for pressing material in a 35 hogshead or similar container, comprising a portable frame with attaching members which project over the edges of the container when the frame is placed in operative position, a pair of complementary clamping 40 members, means for suspending the latter from the attaching members, a lever at each side of the container, each lever being fulcrumed to one clamping member and having a flexible element connected thereto 45 near the fulcrum, and means for adjustably connecting said flexible element to the opposed end of the other clamping member so that the levers may be swung about their fulcrums to draw the two clamping mem-

bers into engagement with the bottom hoop 50 and bottom edges of the container, and means mounted in said frame and cooperating with the clamping members to press material in the container.

7. A device for pressing material in a 55 hogshead or similar container, comprising a pair of opposed complementary clamping members shaped to conform to the bottom edge of the container and each having an inturned flange with a sharpened edge, a 60 lever at each side of the container, each lever being fulcrumed to one clamping member and having a flexible element connected thereto near the fulcrum, means for 65 adjustably connecting each flexible element to the opposed end of the other clamping member so that the levers may be swung about their fulcrums to draw the clamping members inwardly whereby said sharpened edges are forced beneath the edges of the 70 container as the latter rests on the floor, and means adapted to be connected to said clamping members and operable to press material in the container.

8. A device for pressing material in a 75 hogshead or similar container, comprising a pair of opposed complementary clamping members having means to engage the outer surface of the bottom hoop and adapted to extend underneath the bottom of the container, a lever at each side of the container, each lever being fulcrumed to one clamping 80 member and having a flexible element connected thereto near the fulcrum, means for connecting each flexible element to the opposed end of the other clamping member 85 so that the levers may be swung about their fulcrums to draw the two clamping members inwardly to relieve the strain on the hoop and to prevent the bottom of the container from being pushed out, and means cooperating with said clamping member to press material in the container.

In testimony that I claim the foregoing as my own I have hereto affixed my signature.

VIRGIL T. GRABS.
